UNITED STATES PATENT OFFICE

NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed February 26, 1923. Serial No. 621,433.

This invention relates to boiler cleaners and particularly to boiler cleaners utilizing steam or the like as a cleansing fluid.

The invention consists in extending the 5 steam supply pipe to a series of blower units in such a manner as to insure a thorough heating and drying of the portion of said pipe in use, preliminary to opening the valve controlling any of the individual units.

10 A further feature is a provision for automatically opening an orifice for admitting air to a blower unit upon closing of the valve controlling the supply of steam to such unit whereby the partial vacuum arising from 15 condensation of the steam remaining in the unit when the valve is closed will be relieved by clean air from outside the boiler rather than by the gases within the boiler. This will prevent the deterioration of the blower 20 pipes that tends to result from admission thereto of such gases.

In the drawings:

Figure 1 is a view in sectional elevation of a boiler equipped with a series of blower 25 units to which steam is supplied in accordance with this invention;

Figure 2 is a vertical sectional view of an automatic steam control valve for one of said units showing also an automatically controlled air inlet;

Figure 3 is a vertical section on line 3—3 of Figure 2;

Figure 4 is a vertical sectional view illustrating an alternative means for automatically admitting air to a blower unit upon closing of the steam supply valve thereof;

Figure 5 is a cross section on line 5—5 of Fig. 4;

Figure 6 is a vertical sectional view of the 40 steam supply valve to a blower unit showing another alternative form of automatic air inlet;

Figure 7 is a cross section on line 7—7 of Figure 6.

45 In these views the reference characters A, B, C, D, and E designate a series of rotative blower units arranged in suitable locations and at various elevations within a boiler. F is a main valve controlling the 50 steam supply to said units through a vertical

pipe G downwardly extended from said valve to a point below the lowermost of said blower units. H, I, J and K designate successive portions of a steam pipe leading from the lower end of the pipe G and extending successively adjacent the units D, C, B and A. From the end portion K of said pipe the drain pipe L is extended downwardly and a discharge connection M is extended from the lower end thereof to any suitable point. N is a drain pipe communicating with the lower end of the pipe G and discharging into the lower portion of the drain pipe L. G' is a branch supply pipe leading to the unit E from the pipe G, and H', I', J' and K' are branch supply pipes leading respectively to the units D, C, B and A from the pipe portions H, I, J and K, of the supply pipe.

Considering the operation of the invention 70 as so far described, it is to be noted first that the pipe portions H, I, J, K are extended into close proximity to the blower units A, B, C and D so that the length of the branch pipes H', I', J' and K' leading to said units 75 is quite short. The importance of minimizing the length of the branch pipes lies in the fact that upon opening of the supply valve to any unit, the steam admitted thereto is required to initially heat the branch pipe 80 and the condensation of steam occurring during such heating is minimized by making the branches as short as possible.

It is preferred to operate said units in the succession A, B, C, D and E thus securing 85 the advantage that the soot dislodged by the action of any unit will not discharge upon the area previously cleaned by another unit. Blowing the units in the specified succession also presents the advantage that the entire 90 length of the pipe portions H, I, J and K is initially thoroughly heated by delivery of steam to the unit A so that the subsequent operation of the rest of the other units will not result in any condensation in said pipe. 95 As is well understood condensation is undesirable because of the detrimental action on the blower pipes and boiler tubes of the condensed particles of water entrained by the steam.

There will now be described a provision for automatically admitting air exteriorly of the boiler to each unit as the steam supply valve thereof is closed. Thus (referring to Figures 2 and 3) O is a valve in a casing O² controlling the steam supply to the unit, said valve having the upwardly extended stem O'. P is a trigger member pivoted at P' and terminally bearing upon the stem O' for opening the valve. Said trigger is automatically operable by a cam Q secured to the side of a gear Q' fast upon the blower pipe Q². Said gear is adapted to be driven through a pinion Q³ from a chain wheel Q⁴. R is a fitting attached to the casing of the valve O and provided with an air inlet R'. S is a valve controlling said air inlet and provided with an upwardly extended stem S' which above said fitting is provided with spaced upper and lower collars S² and S³, the former fast and the latter loose upon said stem. Between said collars there is disposed a coiled spring S⁴. S⁵ designates a pair of links connecting the sliding collar S³ to an extension S⁶ upon the pivotal end of the trigger P.

In the operation of the described automatic mechanism the cam Q acts during rotation of the blower pipe Q² upon the valve O to open the same during a predetermined portion of each revolution. During the initial valve-opening movement of the trigger P the valve S is acted upon through the links S⁵ to close the air inlet R'. Thus during the period of steam delivery to the unit controlled by the described mechanism the air inlet will be closed preventing escape of steam therethrough. After closing of the valve S has occurred, the subsequent movement of the trigger P necessary to complete opening of the steam valve O is permitted without hindrance from the valve S due to the lost motion connection of the latter valve to the trigger. That is to say, the sliding collar S³ will simply be raised upon the stem S' subsequent to closing of the valve S, the spring S⁴ being at the same time compressed. When the trigger is returned to its normal position shown in full lines in Figure 2, the spring S⁴ will return the sliding collar S³ to its normal lowered position during initial return movement of the trigger and finally the valve S will be unseated so that air will be admitted to the blower pipe as condensation of the steam remaining in said pipe occurs subsequent to closing of the steam valve O.

In the alternative form of the automatic air inlet control shown in Figures 4 and 5, T designates the stem of the steam supply valve and T' a spring acting upon said stem to urge the steam valve to its seat. Said stem is formed with an air passage T² having a vent opening T³ to the casing T⁴ of the steam valve. T⁵ designates a plunger fitting in the upper end of the stem T and provided above said stem with an enlarged head T⁶ for en-

gagement by the trigger T'. Between said head and that extremity of the spring T' which is anchored to the stem T there is compressed a coiled spring T⁸ which urges the plunger T⁵ upwardly but with a force much less than that exerted by the spring T'. The plunger T⁵ is formed with a plurality of longitudinal passages U which when no down pressure is exerted upon the trigger T' are open to the atmosphere, as indicated at U'.

In the operation of the described mechanism, when the trigger T' is actuated, as for example by such a cam as is shown in Figure 2, the first effect will be a depression of the plunger T⁵ since the spring uplifting said plunger is relatively weak as compared to the spring T'. The air inlet opening U' will be closed by this downward shifting of the plunger and further actuation of the trigger T' will lower the stem T to unseat the steam valve. After blowing of the unit controlled by said valve has been completed, downward pressure exerted by the trigger T' will be relieved. This will first result in closing of the steam valve and in a subsequent raising of the plunger T⁵ whereby air will be admitted to the blower unit to relieve the vacuum effect resulting from condensation.

Describing now the form of the invention shown in Figures 6 and 7, U² designates the valve controlling the steam supply to a blower unit and U³ a spring acting upon the stem U⁴ of said valve to normally close the same. U⁶ is a slide bearing in the casing U⁷ of the valve U² through which bearing the stem U⁴ passes, and U⁸ designates a series of longitudinal air intake passages formed in the surface of said stem within said bearing, said passages being so located that when the valve U² is closed communication will be established through said passages between the atmosphere and the portion of the valve casing in open communication with the blower unit. The initial downward movement of the stem U⁴, however, will shift the vent passages U⁸ below the top of the bearing U⁶ so that the air inlets will be closed when steam is being delivered to the unit.

It is to be noted that each of the several described mechanisms for admitting air to a blower unit upon closing of the steam supply valve for said unit possesses in common the feature of automatically shifting the steam supply valve and the air inlet control element in the desired timed relation through a common controlling element.

A considerable prolongation of the useful life of a steam boiler blower results from the automatic admission of air to the unit upon closing of the steam supply valve and thus preventing entry into the unit of deleterious gases and also of the soot particles carried in suspension by said gases which particles will tend to eventually clog the nozzles.

What I claim as my invention is:—

1. In a boiler cleaner, the combination with a blower unit, of a valve controlling the steam supply to said unit, the casing of said valve having an air inlet for admitting air to said unit upon closing of the steam valve for relief of the vacuum effect arising from condensation, and a common automatic means controlling said valve and inlet.

2. In a boiler cleaner, the combination with a blower unit, of a valve controlling the steam supply to said unit, the stem for said valve having a passage providing an air inlet for admitting air to said unit upon closing of the steam valve for relief of the vacuum effect arising from condensation, and means automatically closing said passage during the opening movement of said stem.

3. In a boiler cleaner, the combination with a blower unit including a blower pipe and a valve controlling the steam supply to said pipe, of a common means to move said pipe and actuate said valve, means to admit air to said unit upon closing of said supply valve, said common means also acting to actuate said second-named means.

4. In a boiler cleaner, the combination with a blower unit and a valve for controlling the steam supply to said unit, of means operable to admit air to said blower unit mechanically connected to said valve and operated in common therewith, said means being adapted, by virtue of said mechanical connection, to admit air to said unit only upon complete closing of said steam valve for relief of the vacuum effect arising from condensation.

5. In a boiler cleaner, the combination with a blower unit and a valve structure for controlling the steam supply to said unit, said structure comprising a member movable to and from a seat, of means operable to admit air to said blower unit connected to and movable with said member, said means being adapted to admit air to said unit only when said member is in contact with its seat.

6. The combination with a boiler cleaner including a blower element, a valve controlling the supply of cleaning fluid to said element, a vent for admitting air to said element, and a valve for said vent, of means for actuating said valves, said means being operable to fully close one of the said valves in advance of the opening of the other of the said valves.

7. The combination with a boiler cleaner including a blower element, a valve for controlling the supply of cleaning fluid to said element, a vent for admitting air to said element, and a valve for said vent, of a common means for actuating both of said valves, said means being operable to effect a complete closing of each valve prior to the opening of the other valve.

8. The combination with a boiler cleaner including a blower element, a valve control-

ling the supply of cleaning fluid to said element, a vent for admitting air to said element, and a valve for said vent, of means including a cam and lever for actuating said valves, said means being operable to effect a closing of said air vent valve in advance of the opening of said cleaning fluid control valve and to effect a closing of the cleaning fluid control valve in advance of the opening of the air vent valve.

In testimony whereof I affix my signature.

NORMAN L. SNOW.
